FLAME ARRESTER

Filed Feb. 4, 1944

UNITED STATES PATENT OFFICE

2,420,599

FLAME ARRESTER

Peter C. Jurs, Piedmont, Calif., assignor to
Shand and Jurs Company, a partnership

Application February 4, 1944, Serial No. 521,051

3 Claims. (Cl. 48—192)

1

This invention relates generally to flame arresting devices such as are employed where highly inflammable vapors or liquids are being handled.

Flame arresting devices of the type to which this invention relates are shown for example in Brooks 1,681,698 and are widely used in the petroleum and gas industries for minimizing fire and explosion hazards. They consist of a housing having means for making connection with a storage tank or piping, and a cooling element or tube bank interposed between the inlet and outlet passages of the housing. When in service it is customary to frequently remove the tube bank for cleaning, inspection or possible replacement.

It is an object of the invention to provide an improved flame arrester in which the tube bank may be readily removed and replaced without disturbing connections to the piping system.

Another object of the invention is to provide a flame arrester unit having a simplified body or housing construction, with a part of the housing being attached to and removable with the tube bank.

A further object of this invention is to provide an improved flame arrester having provision for jacking apart sections of the body which are normally clamped together.

Further objects of the invention will be apparent from the following description of the preferred embodiment of the same and illustrated in the accompanying drawing.

Referring to the drawings—

Fig. 1 is a side elevational view in cross-section, illustrating a flame arrester incorporating the present invention.

Fig. 2 is an end elevational view, partly in cross-section, illustrating a flame arrester incorporating the present invention.

Fig. 3 is a view of a part of the clamping mechanism taken along the line 3—3 of Fig. 2.

The apparatus as illustrated in Fig. 1 includes a hollow body or housing composed generally of bell-shaped body sections 10 and 11. These sections are provided with similar flanges 12 and 13 or equivalent means for making connection with the associated piping. Inner enlarged ends of the body sections are provided with flanges 14 and 15 which are in parallel spaced planes perpendicular to the central axis of the body.

Between body sections 10 and 11 there is a flame arrester unit 16 which consists of a cooling element in the form of a tube bank 17 surrounded by a rigid annular shell 18. Tube bank 17 can consist of alternating layers of flat and

2

corrugated metal strips 19 and 20 wound about a central pin or core 21, as shown in Brooks 1,681,698. The exterior of the shell can be provided with a plurality of cooling fins 22 to aid heat dissipation. A handle 23 is mounted on one side of the shell for manual manipulation. Shell 18 and tube bank 17 are fastened together to form a single unit by means of a bolt 24 which passes through shell 18, tube bank 17 and core 21.

The opposed faces of flanges 14 and 15 are provided with machined pads or lands 25 which facilitate insertion and removal of the shell 18 from between the annular machined faces 26 and 27 of flanges 14 and 15.

In order to releasably clamp the body sections 10 and 11 upon opposite sides of the shell, the flanges 14 and 15 are provided with registering holes to receive bolts 28. These bolts have a loose fit in flange 14 but are tapped or threaded into flange 15. Bolts 28 may be turned by use of a wrench applied to heads 29 or by use of a rod passed through holes 30.

In addition to means for clamping the two body parts together, I provide means whereby they can be jacked apart to loosen them from the shell 18. Thus collars 31 are shown attached to the bolts 28 and these collars are positioned as shown in Fig. 1, in spaced proximity to the flange 14. The collars are preferably so dimensioned that they are in close proximity with the adjacent peripheral surface of shell 18 and thus serve to properly align the unit 16 with respect to sections 10 and 11.

In addition to the flange openings and bolts previously mentioned I provide corresponding cooperating slots 32 and 33 in flanges 14 and 15 respectively. These slots are adapted to accommodate bolts 34 which in turn are adapted to swing about pivoted connections 35 between the webs or ribs 36 on body 11. Nuts 37 engage bolts 34 and when tightened serve to clamp the flanges 14 and 15 together. Bolts 34 are likewise provided with collars 38 which are in proximity with the adjacent side portions of shell 18 to align or center the same.

Operation of the above device can briefly be described as follows: Assuming that the body sections 10 and 11 are suitably connected to associated piping and that one desires to remove the flame arresting unit 16 from its normal position between sections 10 and 11, nuts 37 and bolts 28 are loosened whereby body sections 10 and 11 are likewise loosened with respect to each other. Bolts 34 are swung out of the way and flame arresting unit 16 is removed laterally from be-

tween sections 10 and 11, by grasping the handle 23. In the event sections 10 and 11 tend to adhere to the ends of shell 18, continuous rotation of bolts 28 will force collars 31 against flange 14 thereby positively jacking sections 10 and 11 apart.

When replacing flame arresting unit 16 the shell 18 is first inserted between pads 25 and then the unit is thrust laterally to its proper aligned position. Bolts 34 are next swung into position as shown in Fig. 3, whereupon nuts 37 and bolts 28 are tightened thereby clamping bodies 10 and 11 against the shell 18 to form a seal. In normal position shell 18 in effect forms a part of the body and resists inner pressure in the same manner as the walls of the body sections 10 and 11.

I claim:

1. In a flame arresting device of the character described, a pair of hollow body sections adapted to be connected with piping, a flame arresting unit adapted to be interposed between the body sections and comprising a flame arresting core surrounded by a rigid shell, flanges formed on the ends of the body sections adjacent the ends of the shell, a plurality of bolts engaging said flanges and serving to draw the body sections into clamping engagement with the ends of the shell, the bolts on one side of the device being pivotally attached to one of said flanges and engaging in slots in the other flange whereby such bolts can be swung to an out-of-the-way position to facilitate removal and introduction of the flame arresting unit, the bolts on the diametrically opposite side of the device having non-pivotal engagement with said flanges, and collars mounted upon said last mentioned bolts and located adjacent one of said flanges, said collars serving to apply force tending to separate the body sections from engagement with the shell when the bolts mounting said collars are turned in one direction, 40 said collars being dimensioned to engage the peripheral surface of the shell so that the flame arresting unit is generally centralized with respect to the central axis of the body sections.

2. In a flame arresting device of the character described, a pair of hollow body sections adapted to be connected with piping, a flame arresting unit adapted to be interposed between the body sections and comprising a flame arresting core surrounded by a rigid shell, flanges formed on the ends of the body sections adjacent the ends of the shell, and a plurality of circum-

ferentially spaced bolts engaging said flanges and serving to draw the body sections into clamping engagement with the ends of the shell, the bolts of one side of the device being pivotally attached to one of said flanges and engaging in slots in the other flange, whereby such bolts can be swung to an out-of-the-way position to facilitate removal and introduction of the flame arresting unit, the bolts on the diametrically opposite side of the device having non-pivotal engagement with the flanges.

3. In a flame arresting device of the character described, a pair of hollow body sections adapted to be connected with piping, a flame arresting unit adapted to be interposed between the body sections and comprising a flame arresting core surrounded by a rigid shell, flanges formed on the ends of the body sections adjacent the ends of the shell, a plurality of circumferentially spaced bolts engaging said flanges and serving to draw the body sections into clamping engagement with the ends of the shell, the bolts on one side of the device being pivotally attached to one of said flanges and engaging in slots in the other flange, whereby such bolts can be swung to an out-of-the-way position to facilitate removal and introduction of the flame arresting unit, the bolts on the diametrically opposite side of the device having non-pivotal engagement with the flanges, and jacking means mounted upon the non-pivotal engaged bolts and serving to apply force to jack the body sections apart with respect to the shell.

PETER C. JURS.
